Robert H. Hose, Mountain Side, N.J., and Harold E. Steinberg, Philadelphia, Pa., assignors to The Esterbrook Pen Company, Camden, N.J., a corporation of New Jersey

Filed Sept. 12, 1960, Ser. No. 62,105

Term of patent 14 years

(Cl. D74—5)

FIG.1.

FIG.2.

FIG.3.

FIG. 1 is a top plan view of a desk base for a writing instrument showing our new design;

FIG. 2 is a side elevational view; and

FIG. 3 is a front elevational view thereof.

The oval portion seen in FIGS 1 and 3 indicates a depressed opening beneath the transparent covering to receive a picture or indicia.

We claim:

The ornamental design for a desk base for a writing instrument, substantially as shown and described.
